(57) **CLAIM**

The ornamental design for a shoe, as shown and described.

DESCRIPTION

FIG. 1 is a left side view of a first embodiment of a shoe, showing my new design;

FIG. 2 is a right side view thereof;

FIG. 3 is a front view thereof;

FIG. 4 is a rear view thereof;

FIG. 5 is a top view thereof; and,

FIG. 6 is a bottom view thereof.

A second embodiment of the claimed design is a mirror image of the design shown in FIGS. 1-6.

In the drawings, the broken lines represent environmental subject matter that forms no part of the claimed design.

1 Claim, 4 Drawing Sheets
